METHOD OF MAKING FABRICATED ARTICLES

Jon Gregg, New Hope, Pa.

Application September 29, 1944, Serial No. 556,399

3 Claims. (Cl. 12—146)

1

This invention relates to fabricated articles and methods of making the same. It is particularly directed to an improved process for making outsoles for footwear, rugs and the like articles.

An object of this invention is to improve the method described in my co-pending application Serial No. 401,179, filed July 5, 1941, issued as Patent No. 2,361,938 on November 7, 1944.

Another object of this invention is to provide a process of the character described comprising winding a flexible strip with moldable, vulcanizable, thermosetting or thermoplastic material covering substantially an entire side, and then causing the material to soften, flow and unite the windings of the strip without any substantial overflow at the top and bottom surfaces of the wound strip.

Another object of this invention is to provide an economic process of the character described which will result in a strong, durable and comfortable outsole.

Other objects of this invention will in part be obvious and in part hereinafter pointed out.

The invention accordingly consists in the combination of steps, features of construction, combinations of elements, and arrangement of parts which will be exemplified in the method and construction hereinafter described, and of which the scope of application will be indicated in the following claims.

In the accompanying drawing, in which is shown one of the various possible illustrative embodiments of this invention,

Fig. 1 is a side elevational view of apparatus for carrying out the invention;

Fig. 2 is a top plan view of the winding table used in carrying out the invention;

Fig. 3 is a partial, side elevational view of the sole as it comes off the winding table, with parts broken away;

Fig. 4 is a cross-sectional view taken on line 4—4 of Fig. 3;

Fig. 5 is a top plan view of a sole made in accordance with the process embodying the invention;

Fig. 6 is a cross-sectional view taken on line 6—6 of Fig. 5;

Fig. 7 is a top plan view of a temporary mold used to carry out the inventive process;

Fig. 8 is a cross-sectional view taken on line 8—8 of Fig. 7;

Fig. 9 is a top plan view of the mold used for pressing the outsoles under heat and pressure;

2

Fig. 10 is a view similar to Fig. 4 and illustrating a modification of the invention;

Fig. 11 is a view similar to Fig. 10 and illustrating another modification of the invention;

Fig. 12 is a view similar to Fig. 11, but showing the sole after molding under heat and pressure; and

Fig. 13 is a transverse, cross-sectional view illustrating a modification of the inventive process.

In my co-pending application Serial No. 401,179, issued as Patent No. 2,361,938 on November 7, 1944, there is described a method of making an outsole comprising the application of a strip of uncured rubber or synthetic moldable material in tacky condition to a side of a braided strip, then winding the stuck-together strips into the general form of an outsole, and pressing the same in a mold under heat and pressure to produce the outsole. In said co-pending application the strip of uncured rubber or other moldable material is defined as being of less width than the braided strip, and the edges of the moldable strip are defined as being disposed inwardly of the edges of the braided strip. The reason for spacing the edges of the strip of moldable material from the braided strip is so that during the molding process the rubber will not flow over the top and bottom of the braided strip and gum up the surfaces of the sole. After the molding operation, the thermoplastic or moldable material flows substantially to the upper edges of the braid. Thus in curing the sole, the pressure of the mold and the heat of the vulcanization cause the rubber to flow, and in the finished sole the rubber is actually as wide as the braid.

In the present invention the strip of moldable material is substantially as wide as the braided strip but does not flow over the top and bottom surfaces of the sole during the vulcanizing or molding process, or while the sole is subjected to heat and pressure.

The prevention of overflow or gumming up of the tread surface can be accomplished in several ways. The first is by the use of semi-cured rubber, that is the rubber compound is subjected to a period of vulcanization or curing insufficient to totally cure or vulcanize the rubber. Another way of accomplishing the desired result is to use flow resisting rubber. The achievement of such a product is entirely dependent on the amount of sulfur and the type and amount of accelerator used so that the rubber will begin curing prior to too great a pressure being applied in the mold. If a certain non-cured rubber mix

or compound requires a certain time, a certain temperature and pressure, to wholly cure it, then additional accelerator is added so that the compound will cure faster at the temperature and pressure used, that is it will cure before it has a chance to flow over. If a Captax-Altax-Methyl Tuads acceleration with Kalite No. 1 filler is used, it will probably give a better rubber compound which is flow resistant. It may be necessary to add litharge to the compound to get a fast enough cure.

Another way of accomplishing the desired result is to use a thermosetting resin which is dipped or sprayed on all sides with a thermoplastic resin. This could be accomplished by extruding the thermosetting resin and then passing it through rollers which would coat it with a thermoplastic resin. The thermosetting resin should cure at about 50° below the curing temperature, and the thermoplastic resin should cure around 10° before the curing temperature. Thus the thermosetting resin will cure before the thermoplastic resin. The accelerated curing will retard the flow. The thermosetting resin might also be cured outside of the press and the thermoplastic resin cured in the press.

In Fig. 1 of the drawing, there is shown apparatus 10 to carry out part of the inventive process. The apparatus 10 comprises an extruder 11 for extruding a strip 12 of moldable thermoplastic, thermosetting, or vulcanizable material. The strip 12 passes between rollers 14 for applying a tackifier to the strip if it is not sufficiently tacky in itself. The lower roller may run in a trough 15 and a solvent for the moldable material may be applied to the upper roller by means of a drip tank 16. The strip 12 is united with a flexible fibrous strip such as a braided strip 17, by pressing between rollers 18. The strip 17 may comprise braided fibrous yarn such as cotton, wool, jute, hemp or the like fibers, or may be of any suitable strip of flexible material preferably fibrous, porous or absorbent material so that the moldable material may penetrate the same during the molding process as will appear hereinafter. Instead of a solvent, a plasticizer or an adhesive may be applied to strip 12; or heat may be applied (as by heated rollers) to cause it to become tacky. If desired, the material may be extruded in tacky condition. Also if desired, an adhesive may be applied to the strip 17 to cause strip 12 to be united therewith.

The pressed-together strips may pass through a guide 20 and be wound on the usual winding table 21. As shown in Fig. 4 of the drawing, the strip 12 is substantially as wide as the braided strips 17. The strip 12 may, as stated above, be semi-cured rubber compound, that is, it is a rubber compound which, after a period of vulcanization or self-curing shows chemical and physical properties such as tensile, swell in gasoline, hardness, elongation, shape, etc., which are substantially different than those obtained by a further period of vulcanization or self-curing.

The solvent for semi-cured rubber to render it tacky may be in the form of low grade gasoline, aromatic hydrocarbons such as benzene, or rubber cement can be used which could be spread on the semi-cured rubber. The strip 12 may also be in the form of a flow resisting rubber compound provided with excess amount of accelerator than is usual for curing at the temperature, pressure and time required for a normal amount of accelerator. The strip 12 may also be made of a plastic which will cure at low temperature prior

to application of pressure. A thermoplastic resin could be used.

After the strip is wound on table 21, it may be premolded or compressed in the temporary mold or premolder 30 shown in Figs. 7 and 8. The mold 30 comprises a pair of complementary mold members 31 and 32 having cutouts to receive the sole. Mold member 32 is slidable in mold member 31 and may be closed by means of clamped levers 33. Hand pressure is applied to cause the windings of the outsole to stick together sufficiently so that the outsole can be handled, stored and transported to the permanent molds. A top plate 35 may be used to press the sole into the mold. The moldable material must be sufficiently tacky or adhesive to permit the turns to stick together sufficiently to permit handling of the sole. Thereafter the sole is placed in a permanent mold 40 shown in Fig. 9, and the moldable material is cured under heat and pressure.

The mold 40 likewise comprises complementary mold members 42 and 43 having complementary cutouts 42a and 43a to receive the sole. A top plate 45 may be employed to press the sole into the mold. A plunger which fits into the mold may be used instead of a top plate.

In Fig. 5 there is shown a sole S in accordance with the present invention. During the curing, the semi-cured or flow resisting rubber flows and penetrates into the interstices of the braid to unite the windings. With the process described herein there will be substantially no flow over the top and bottom of the sole.

In Fig. 10 there is shown a wound sole prior to molding under pressure and heat. In said figure there is shown a strip 12a which replaces the strip 12. Strip 12a comprises a core 50 of thermosetting material coated by a coating 51 of thermoplastic material as described above. The thermosetting material 50 cures faster than the curing temperature for the thermoplastic material and since it cures faster, it does not have a chance to flow over the top and bottom of the sole.

In Fig. 11 there is shown a wound sole prior to molding. In making said sole there is employed a moldable strip 12b which is thicker in the middle than the ends. The strip 12b is also substantially as wide as the braided strip 17. During the molding process there will be substantially no overflow because there is less moldable material at the edges of the strip than at the middle.

In Fig. 13 there is illustrated another modification of the invention. In Fig. 13 there is shown a strip 12c of moldable or thermoplastic material, either synthetic material or crude rubber. The upper and lower edges of the strip 12c may be semi-cured by passing the strip between a pair of heated blocks 80. The strip 12c may also be thicker at the middle than at the edges if desired. When the strip 12c is combined with the braided strip and placed in the mold, the middle part of the strip will flow more than the edges, and thereby overflow of the moldable material will be prevented. During the molding process it has been found that the rubber flows more at the top and bottom edges than at the middle because the upper and lower edges of the strip are closer to the heated parts of the mold. By first semi-curing the edges, a retarding of flow at the edges will result during the final curing operation.

Plastic strips could be adhered to the braid by the use of water and alcohol solutions, for ex-

ample, Durez resin, certain amberlite resins of Rohm and Haas, and certain Bakelite resins are water soluble. Eastman Tenite and Vinylite are soluble in esters and ketones such as acetone, methyl-ethyl ketone, ethyl acetate. The polystyrene plastics are also soluble in ketones and esters. The plastic strip can be passed through a roll coated with one of the suitable solvents, so that it will soften. It is possible to cure rubber and plastics without heat and pressure or only by the application of pressure and without heat. There are rubber accelerators and plastic catalysts to do this self-curing. It is also possible to apply a solvent to the plastic and then by pressure alone to cause the plastic to flow into the braid. When using rubber or resin strip binders, the same may be given tackiness by spraying with adhesive. Rubber may be sprayed with rubber cement. A tacky resin may be added to the base resin to make the strip tacky. Rosin, pine tar or paraflux are good tackifiers for rubber and would work with plastics.

A solution of rubber or a resin could be sprayed on the braid, allowed to dry and then brought back to a tacky condition by application of a solvent to the rubber or resin. Furthermore, such resin or rubber may be rendered adhesive by application of heat prior to winding so that the turns will stick together to permit handling.

Another method of carrying out the invention is to coat both sides of a plastic strip with a tackifier or with an adhesive or applying a solvent to opposite sides of the plastic strip and then pressing the plastic strip to one side of a flexible fibrous strip, such as braided cotton, jute, manila, or the like material, then winding the braided strips together into the general form of an outsole, then pressing the outsole in a temporary mold 30, and then molding in a mold 40 under heat and pressure. The fact that the plastic or rubber strip is tacky on opposite sides, permits one side to be applied to the braided strip and also permits the windings of the strip to stick together particularly when pressed in the temporary mold 30 to permit handling as it is transported to the mold 40 for the final curing and molding operation.

Although there has been above described a process of making an outsole, it will be understood that other articles may be made in accordance with the process described above. Thus rugs can be made by winding the fibrous flexible strip spirally together with the thermosetting, thermoplastic or other moldable material or uncured rubber. Furthermore, instead of winding the strip it may be arranged in parallel layers. After the molding process, various articles may be died out. Thus, for example, a sole may be died

out of a layered article made in the manner above described.

Furthermore, although the drawing describes the fibrous strip 12 as being a braided strip, it will be understood that any suitable strip may be substituted such as a woven or knitted strip, or a rope.

It will thus be seen that there is provided a device and method in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

- 20 1. A process of making a layered article, comprising arranging strip portions of semicured rubber between strip portions of flexible fibrous material of the same width so that the semicured material is disposed between the strip portions of the flexible fibrous material, and then subjecting the article to heat and pressure in a mold for curing the semicured rubber to unite the flexible strip portions.
- 25 2. A process of making a layered article of a thickness equivalent to the width of strips of flexible fibrous material, comprising arranging strip portions of said fibrous material in layers with intervening strips of moldable material which are thicker at their midportions than at the edge thereof, pressing said strip portions together and subjecting the article to heat and pressure in a mold for causing the moldable material to soften and unite adjacent flexible strip portions.
- 30 3. A process of the character described, comprising semi-curing the edge portions of a strip of vulcanizable material, then applying the strip to one side of an elongated flexible strip of fibrous material, winding the strips together in the form of an outsole and vulcanizing in a mold under heat and pressure.
